UNITED STATES PATENT OFFICE.

LEWIS LARSEN, OF MENOMINEE, MICHIGAN, ASSIGNOR TO HEYWOOD-WAKEFIELD COMPANY, OF BOSTON, MASSACHUSETTS, A CORPORATION OF MASSACHUSETTS.

DAVENPORT BED.

Application filed February 6, 1925. Serial No. 7,246.

The general object of my invention is to provide a davenport bed which shall be simple and inexpensive in construction; which shall be durable in use and which shall be 5 of such construction that it can be converted with little effort from its condition as a davenport to that of a bed and vice versa.

Another object of my invention is to provide a davenport bed construction which 10 when in davenport condition will look like an ordinary davenport of the same type, i. e. which shall not bear the "ear marks" of a convertible piece of furniture.

Again, I aim to provide a davenport bed 15 construction in which the same seat surface or cushion which is uppermost in davenport condition shall also be face up when in bed condition, the parts being of such construction that when in davenport condition a compact arrangement is provided in which the 20 seat or movable cushion is directly supported by a fixed or permanent cushion, thereby providing a double cushion effect when in davenport condition.

25 A special object of the invention is to provide mechanism of simple, inexpensive and durable character for the purpose of guiding the cushion in the act of converting the furniture to its respective uses.

30 My invention consists generally of a davenport bed construction of the form, arrangement, construction and cooperation of the parts whereby the above named objects, together with others that will appear herein-after are attained; and my invention will be 35 more readily understood by reference to the accompanying drawings which illustrate what I consider, at the present time, to be the preferred embodiment thereof.

40 In said drawings:

Fig. 1 is a perspective view of a davenport bed embodying my invention.

Fig. 2 is a detail enlarged sectional view substantially along the line 2—2 of Fig. 1.

45 Fig. 3 is a fragmentary horizontal section of one end of the davenport bed arranged in bed position, parts being broken away for illustrative purposes.

Fig. 4 is an end view showing the parts in 50 davenport condition, a portion being broken away for illustrative purposes.

Fig. 5 is a view similar to Fig. 4 but showing the parts as in condition for use as a bed, and

Fig. 6 is a detail sectional view substantial- 55 ly along the line 6—6 of Fig. 2.

For the sake of convenience in terminology the condition of the furniture as in the folded or compact condition shown in Figs. 1, 2 and 4 will be referred to as the davenport condition 60 and the unfolded or open condition shown in Figs. 3 and 5 as the bed condition.

In the davenport condition my construction appears to the observer as an ordinary davenport of that particular type; that is to 65 say it is lacking in those "ear marks" which so often characterize convertible furniture. It, therefore, may be used with the other pieces to a suite of the same type of furniture 70 of non-convertible character.

I have chosen to illustrate a davenport of the so-called reed type but this, it should be understood, is by way of illustration and not by way of limitation. Thus, there is provided a reed fabric comprising the back portion 1 and the end portions 2 which are of usual or desired form or configuration. This reed fabric is secured to a suitable supporting frame which may be generally of known construction in so far as the upper portion is 75 concerned. Inasmuch as the lower frame construction is involved in my invention it 80 will be described in necessary detail.

Thus, there is provided an open rectangular frame composed of the front and rear 85 rails 3 and 4, respectively, which are cross connected at the ends by the end members 5. The open frame thus formed is supported by the necessary legs 6.

Supported on the open frame just described is what will be hereinafter termed a sub-cushion. It is composed of an open frame 7 between spaced portions of which there extend a plurality of members 8 upon which the desired number of spiral springs 9 are supported. The springs 9 are enclosed by means of a covering 10 of any suitable material. Inasmuch as this is not exposed to view except during the brief period of conversion from bed to davenport condition 100 or vice versa a good cotton cloth covering is satisfactory. In order to form a suitable cushion padding material is interposed between the springs and the cloth covering. The frame of the sub-cushion rests upon the open frame of the davenport proper and is held against shifting by means of the clips 105 11.

Superposed upon the sub-cushion is what will be termed a seat cushion. The seat cushion is composed of a rectangular frame 12 similar to the frame 7 of the sub-cushion, but of greater depth so that the front member 12' thereof is disposed forwardly of the front member of the sub-cushion frame. Extending between spaced members of the seat cushion frame 12 are members 13 on which a plurality of spiral springs 14 (similar to the springs 9 of the sub-cushion) are mounted. A covering 15 is provided to enclose the springs and inasmuch as the seat cushion will be used most, it is preferably provided with padding 16 over which a suitable outer covering 17 of tapestry, velour or the like is placed.

The seat cushion, it will be noted rests directly upon the sub-cushion when the parts are in the davenport condition. Thus, the user secures the advantage of both sets of springs. A much more comfortable construction is, therefore, provided than would be the case if the seat cushion were spaced away from the sub-cushion in davenport condition. In other words, the springs need not be so stiff as would otherwise be necessary to support the localized weight to which the davenport is subjected when a person reposes in sitting posture thereon. At the same time the springs afford sufficient support when the structure is in bed position, even though but one set is in action at any given point because the weight of the occupant is not then localized but is distributed over a much greater area.

When a bed is desired the seat cushion is moved to the position shown in Figs. 3 and 5. This may be easily accomplished by the leverage mechanism which I am about to describe, but before doing so it should be noted that in bed position the seat cushion still presents the same surface uppermost and which is then in substantially the same plane as the top surface of the sub-cushion, thus providing a bed of substantially full width. With the mechanism which I have provided it is not necessary that the seat cushion revolve as a simple shifting thereof forwardly or rearwardly, as the case may be, through an arc-like path disposed in its respective davenport and bed positions.

Coming now to the mechanism for guiding the seat cushion in its swinging movement there is provided at each end levers 18 which are cross-connected by a rod 19. The levers 18 are pivotally secured to the stationary furniture frame as indicated at 20. Assuming now that the parts are in the davenport condition the lever 18 has a portion adjacent its pivot which is substantially horizontally disposed, one end of which merges with the substantially right angularly disposed portion 18^a. On the opposite side of the pivot 65 there is a portion 18^b which inclines up-

wardly rather abruptly and a portion 18^c which inclines upwardly at a lesser angle. The angular disposition of these parts is such as to permit them to extend forwardly over the davenport frame when the parts are in bed condition (see Fig. 5). The upper end of the lever 18 is attached at 18^d to the frame of the seat cushion.

Also pivoted to the davenport frame as at 21 is a lever which (in davenport condition) 75 has a relatively short upwardly and rearwardly inclined portion 22, a substantially right angularly disposed portion 22^a, a generally upwardly and rearwardly extending portion 22^b terminating in a downwardly extending portion 22^c which is attached to the seat cushion frame at 23. It will be understood that there is one of these levers at each end but inasmuch as they are alike in construction a description of one will suffice. In 85 order to prevent interference of the levers 18 and 22, the lever 22 is laterally offset at 22^d (see Fig. 3).

In order to make the conversion operation more convenient the seat cushion is preferably provided with strap handles 24 at opposite ends. The swinging operation is well indicated by the full line position of the parts in the davenport and bed conditions and the dotted line intermediate positions shown in 95 Figs. 4 and 5.

It remains to be stated that when the seat cushion moves to the bed position that the front panel 25 which is composed of a rectangular frame, rigidly secured to the frame 100 of the seat cushion, and the fabric outer covering 27 moves with the seat cushion and thus serves to support the forward edge thereof when in bed position. That is to say in bed condition the front panel 25 rests upon 105 the floor. The rear edge of the cushion is, of course, supported by the levers 18 and 22 which at this time extend forwardly from both ends of the davenport frame.

It should also be noted that I have provided 110 springs 28 and 29 to facilitate the shifting operations of the seat cushion to and from its respective positions. Thus the spring 28 is connected at one end to the portion 18^d of the lever 18 and at the other end to a stationary 115 part of the davenport frame. When the parts are in davenport condition the spring 28 is in tension as indicated in Fig. 4. Thus it exerts a force tending to swing the seat cushion to its bed position but this it cannot 120 do because of the weight of the seat cushion. It should be apparent, however, that it does assist the operator when the shifting operation is undertaken. Also that when the seat cushion is moving from the bed position to 125 the seat position that the spring will "break" the fall thereof. That is to say, it will let the seat cushion find its place gently and with but little effort upon the part of the operator.

The spring 29 is secured at one end 30 to the 130

davenport frame and at the other, through the medium of the chain 31, to the lever 18 at point 33. The spring 29 is inactive when the parts are in or near their davenport position.

5 When, however, the parts approach their bed position the spring 29 begins to function. That is to say it is placed under tension or distended, thus operating with respect to the bed position of the parts in a manner similar 10 to the spring 28 with respect to the davenport position. Hence it assists the operator, gently bringing the seat cushion to rest and also in starting it upon its return path when desired.

15 From the foregoing it should be obvious that the many advantages of my invention are attained by the described structure but inasmuch as this will suggest modified constructions to those skilled in the art to which this 20 appertains I do not wish to be limited to the details disclosed except only as may be necessary by limitations in the hereunto appended claim.

I claim:

25 A davenport bed construction embodying therein, a davenport frame, a sub-cushion mounted on said frame, a seat cushion including a frame arranged above the sub-cushion

when in davenport position, means for guiding the seat cushion to and from bed position 30 and including pairs of associated lever and link members operatively connected to said davenport frame and the seat cushion respectively, said lever members each having arms extending beyond its point of connection with said davenport frame and being offset inwardly to extend under the rear portion of the seat cushion frame when in bed position to be engaged by and to support said seat cushion frame in said last mentioned position, and 40 two springs associated with each pair of said lever members, both of said springs being secured at one end to said davenport frame, the other end of one spring being connected to the arm of its associated lever member and the 45 other end of the other spring being connected to said lever member between its ends by means of a flexible connecting member, said springs being brought into tension in alternation and assisting in the movement of the 50 seat cushion from davenport position to bed position and vice versa.

In testimony whereof, I have hereunto set my hand, this 30th day of January, 1925.

LEWIS LARSEN.
